(57) **CLAIM**

The ornamental design for a paper holder strip, as shown and described.

DESCRIPTION

FIG. 1 is a front perspective view of the paper holder strip of the present invention showing our new design with the phantom lines depicting solely environmental structure and forming no part of the claimed design;

FIG. 2 is an end view thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a cross-sectional view thereof taken about line 7—7 of FIG. 1; and,

FIG. 8 is a top perspective view illustrating that the paper holder strip of the present invention can be formed having differing lengths.
